UNITED STATES PATENT OFFICE.

EDWARD C. DEAN, OF WASHINGTON, DISTRICT OF COLUMBIA.

ANTI-FRICTION ROLLER.

SPECIFICATION forming part of Letters Patent No. 365,506, dated June 28, 1887.

Application filed December 24, 1886. Serial No. 222,453. (No model.)

To all whom it may concern:

Be it known that I, EDWARD C. DEAN, a citizen of the United States, residing at Washington, in the District of Columbia, have invented 5 certain new and useful Improvements in Anti-Friction - Rollers; and I do declare the following to be a full, clear, and exact description of the invention, such as will enable others skilled in the art to which it appertains to make 10 and use the same, reference being had to the accompanying drawings, and to the letters of reference marked thereon, which form a part of this specification.

This invention relates to certain improvements in anti-friction rollers, and it has for its 15 objects to provide a roller that insures durability and cheapness, as well as an easy-moving roller. These objects I attain by the means illustrated in the accompanying drawings, in 20 which—

Figure 1 represents a horizontal sectional view; Fig. 2, a detail of one of the sides removed, and Fig. 3 a cross-section.

In the drawings, the letter A indicates the 25 sides of the roller connected together by the solid core B.

C indicates a series of anti-friction rollers arranged around the periphery of the solid core. These rollers C are provided with trunnions or journals D, which bear in annular 30 grooves E in the sides A. It can be seen by the drawings that the rollers are concave at their centers, having at the ends a narrow bearing-surface which rolls upon the solid core,

before described. The core and the sides, being 35 bolted to any suitable object, remain stationary.

This invention is especially designed for cable roads, at the curves particularly, where a tremendous strain exists at all times. The 40 cable traveling upon the surfaces of the rollers causes them to roll upon the solid core and upon their trunnions in the annular grooves, the most of the strain being upon the surface of the solid core, the trunnions of the rollers 45 serving merely as guides in the annular grooves.

I do not limit myself to the use of this invention to cable roads; but it can be adapted to other uses, such as blocks and tackles, pulleys, &c.

Having thus fully described my invention, what I claim, and desire to secure by Letters Patent, is—

The combination, with the sides A, having 55 abutting solid cores B, and secured together by transverse bolts, of the anti-friction rollers provided with journals D, arranged to travel in annular grooves in the sides A, and having concave surfaces over which a traveling cable 60 or belt may pass, substantially as specified.

In testimony whereof I affix my signature in presence of two witnesses.

EDWARD C. DEAN.
